BAG MAKING MACHINE

Charles F. Schultz and Ira E. Schultz,
Oakland, Calif.

Application February 17, 1940, Serial No. 319,486

23 Claims. (Cl. 93-8)

The present invention relates to improvements in bag making machines, and its principal object is to provide a machine of the character described that is fully automatic and makes bags from a continuous roll of Cellophane or similar material which can be sealed by the mere application of heat under pressure.

More particularly it is proposed to provide a machine in which a ribbon of Cellophane is fed from a roll disposed at the rear end of the machine, is periodically advanced by means disposed at the front end of the machine and is subjected to various bag-forming operations intermediate the feed roll and the advancing means.

It is further proposed in the present invention to provide certain improvements in the feed roll mounting whereby the latter may be readily centered with respect to the machine and is allowed free rolling action during the periods of advance, while automatically operating means are provided for stopping rotation during the periods of rest.

It is further proposed to provide means for turning the advancing ribbon into tubular form and to provide an auxiliary means for creasing the advancing material at opposite edges where a square bag is desired.

It is a further object of our invention to provide certain improvements in connection with the cutting apparatus whereby a previously formed bag is separated from the ribbon and the new end thereof is folded over the remainder of the tubular ribbon to provide a new bottom for the next bag.

It is further proposed to provide a movable template over which the extreme end of the ribbon is turned and which thereafter is automatically retracted so as to allow of sealing operations.

It is further proposed to provide separate heating means for the transverse seam at the bottom of the bag and the longitudinal seam, the said heating means being separate to accommodate the template previously mentioned, when in retracted position.

A further object of our invention is to provide certain improvements in the advancing means for the ribbon and in the gripping means for the latter and to provide a general organization in which most of the essential moving parts are driven from a common shaft whereby the machine is rendered comparatively simple.

Further objects and advantages of our invention will appear as the specification proceeds.

and the novel features thereof will be fully set forth in the claims hereto appended.

The preferred form of our invention is illustrated in the accompanying drawings, in which:

- 5 Figure 1 shows a side elevation of our machine with the near side of the frame removed;
 Figure 2, a front view of our machine;
 Figure 3, a transverse section taken along line 3-3 of Figure 1;
 Figure 4, a detail view in longitudinal section illustrating the heater operating means;
 Figure 5, a detail view of the same mechanism as seen from line 5-5 of Figure 4;
 Figure 6, a detail view in longitudinal section 10 illustrating the cam drive for the cutter; and
 Figure 7, a fragmentary section illustrating an eccentric drive for the advance means; and
 Figure 8, a sectional detail view taken along line 8-8 of Figure 1, and
 Figure 9, an enlarged sectional detail view of the gripping means of our invention.

15 While we have shown only the preferred form of our invention, we wish to have it understood that various changes or modifications may be made within the scope of the claims hereto attached without departing from the spirit of the invention.

The frame 1 of our machine, preferably comprises two sides 2, only one of which is shown 20 in Figure 1, the sides being supported on legs 3 and held in spaced and parallel relation by suitable spacers 4. At the rear end of the machine are provided uprights 5 and the latter have arms 6 projecting rearwardly therefrom for supporting a horizontal shaft 7 on which the roll 8 of Cellophane or similar material is mounted.

The shaft 7 is supported in notches 9 in the arms 6 and one of the notches is threaded to receive a correspondingly threaded section of 25 the shaft so that the latter may be adjusted in its position in the notches by a turning movement of the shaft for effecting proper centering of the roll with respect to the remainder of the machine. The threaded portion of the shaft is 30 made revolvable relative to the remainder of the shaft. A suitable construction for this purpose is shown in Figure 8 where the threaded portion is furnished by a sleeve 7' having a handle 7''. The sleeve is revolvable on the shaft 40 and held against axial motion between the brake drum 17 and the head of a bolt 17' threaded into the end of the shaft 7.

The ribbon of Cellophane is drawn from the roll as indicated in dotted lines, first underneath a horizontal roller 10 of a swinging frame 11

pivoted on the main frame, as at 12, thence over the roller 13 supported in the arms 6, and from there underneath the forming plate 14 by the gripping means 15 supported by the swinging frame 16. The latter frame periodically pulls the ribbon forward and the frame 11 serves as a tensioning means for maintaining the ribbon taut.

The roll of Cellophane has a brake drum 17 associated therewith and a brake shoe 18 pivoted, as at 19, is adapted to bear on the brake drum to arrest movement thereof. A rod 20 connects the free end of the brake shoe with the frame 11 near the pivot 12 thereof, the rod having sliding connection with the frame as at 21, and being limited in outward movement by a cotter pin 22.

The frame 11 extends slightly beyond the pivot, as at 23, and this extension is connected to an intermediate portion 24 of the rod 20 by means of a spring 25. With the ribbon in a position of rest, the various parts occupy the positions indicated in Figure 1. When the ribbon is advanced by the gripping means, it first tends to lift the roller 10 of the frame 11, which allows a short portion of the ribbon to advance. The lifting of the roller 10 causes the rod 20 to be raised by the means of the cotter pin 22 which releases the brake so that the roll is free to rotate.

When the advance movement of the ribbon ceases, the roll continues to rotate, but the slack in the ribbon created by the continued rotation is taken up by the roller 10 on the frame 11, which immediately descends under the influence of the spring 25, which latter also pulls downwardly on the free end of the brake shoe through the rod 20 for setting the latter.

The free sliding connection between the frame 11 and the rod 20 allows the latter to go somewhat beyond the cotter pin 22 when the brake is set, so as to allow the rod 10 to take up all the slack that may develop during the operation of the brake-setting apparatus.

It will thus be understood that the roll is free to rotate during each feeding operation, and is positively held against rotation during each period of rest.

The forming plate 14 extends lengthwise over the machine and may be made as a single plate if an ordinary tubular bag is desired. In the preferred form, shown in the drawings, which is intended for making square bags, the forming plate is made of two spaced members 38 and 39 held in spaced relation by a central longitudinal bar 32, this construction providing lateral grooves 33 in the forming plate. Any other suitable construction may, of course, be substituted for the one shown and described as long as it performs the desired function.

The forming plate is supported, preferably in such a manner as to bring the grooves substantially into alignment with the upper ends of the sides 2 of the frame, which latter are provided with inwardly turned flanges 34. The rear end of the forming member is hinged, as at 35, to a frame 36 suspended from the shaft 37 provided in the upper end of the uprights 5. The front portion of the forming plate is supported on a bar 38 having its front end pivoted on one of the spacers 4 and having its rear end resting on the second spacer 4 provided rearwardly of the first one. The second spacer is preferably mounted eccentrically with respect to a supporting bar 4' whereby the level of its upper face may be slightly adjusted.

The front of the bar 38 is preferably provided with lateral arms 39 to furnish a better support for the front edge of the forming plate.

The rear end of the lower member of the forming plate is made to flare upward, as at 40, to guide the central portion of the ribbon underneath the forming plate.

The ribbon which is identified by the numeral 8', is sufficiently wide for folding over the forming plate to provide centrally overlapping margins and to additionally provide material for the creases to be formed in the sides of each bag.

The creases are formed by the plates 41 supported on brackets 42, which latter again are supported on transverse rods 43. A pair of brackets are supported on each rod 43, one for each plate 41, and the brackets are made to move along side of the rod in opposite directions by means of reverse threads 44.

Each plate has two brackets 42, one for each shaft 43, and the two shafts are interconnected by the chain drive 45. A hand wheel 46 is provided for one of the shafts 43, and it will be readily seen that the two creasing plates 41, may be moved toward one another for entering the grooves 33 of the forming plate or away from one another for removal from the grooves by the mere operation of the hand wheel 46.

Overlying the forming plate, we provide a heater frame 47, substantially coextensive in length with the forming plate, and having its rear end pivoted to the frame 36, as at 48. A spring 49 has a tendency to draw the heater frame upward, but the latter is normally held against the tension of the spring with its front section in substantially parallel relation to, and slightly spaced from the front section of the forming plate, as shown in Figure 1.

The rear section of the heater frame supports, on a yielding bracket 50, two rollers 51, which ride on the folded margins of the ribbon of Cellophane, and are arranged at a slight angle so as to have a tendency of urging the two margins toward one another.

A transverse horizontal bar 52, suspended from the heating frame by means of vertical rods 53, rides on the folded margins of the Cellophane ribbon, and has a tendency to flatten them out against the surface of the forming plate. Two rods 54, suspended from the shaft 37 and engaging with the sides of the ribbon, have a tendency to give a first initial turn to the ribbon which emanates from the rod 13 perfectly flat.

Additional elements and guide means of conventional character may be provided, of course, to cause the advancing ribbon of Cellophane to form itself around the forming plate into the shape of a tube with overlapping margins over the center of the forming plate.

A yielding horizontal finger 55' carried by the bracket 50, is used for guiding one of the margins to fold underneath the other.

For initiating operation of the machine, the ribbon is guided manually underneath the forming plate, with the plates 41 retracted. The side edges of the Cellophane are then folded over the forming plate whereupon the plates 41 are moved inwardly to enter the grooves 33 and to form the lateral creases in the ribbon. The extreme margins are folded over the edges of the forming plate manually, and are smoothed into the overlapping position shown in Figure 3. During this manual initial positioning of the ribbon, the heater frame should be allowed to swing upward and the latter is now brought down to the working position of Figure 1, with the rollers 51 riding

on the margins of the Cellophane and the transverse bar 52 smoothing and flattening the overlap.

After the Cellophane has been thus positioned, the intermittent advance of the same is taken care of by the swinging frame 16 and the gripping means 18 carried thereby. The advance end of the ribbon at the front end of the forming plate is formed into a bottom seam for the bag during each operation by means to be described hereafter, and the gripping means take hold of the bottom seam thus formed and through the latter, pull the entire ribbon forward by the length of one bag, whereupon the latter length is separated from the ribbon by the cutting means to be described later, to allow a new seam to be formed for the next bag.

The swinging frame 16 is pivotally mounted on a sleeve 55 supported in the bearing 56 at the lower front end of the machine. It is operated to swing toward the machine and away from it by means of a link 57 pivoted to the frame, as at 58, and to an arm 59, as at 60.

The arm 59 projects from a sleeve 61 revolvable on a transverse shaft 62, the sleeve having a short arm 63, which is rocked through the connecting rod 64 by an eccentric α on the main drive shaft 65. The latter receives rotary motion through suitable gearing from the electric motor 66, or any other suitable source of power.

The arm 59 is formed with a slot 67 in which the pivot 68 engages and this slot is curved in such a manner that no matter at what point the pivot 68 engages therewith, the back swing of the frame 16 will always terminate at the same point with respect to the front edge of the machine, while the forward swing, away from the machine may be varied to any desired degree. Thus it is impossible for an operator to make any adjustment which would cause the frame 16 on its back swing, to strike the front face of the machine and to thereby cause all operations to stop.

For gripping the bottom end of the bag at the front end of the ribbon, we provide the two gripping fingers or plates 69 and 70 pivoted in the upper end of the swinging frame, as at 69 and 70, so that one finger overlies the other in gripping relation relative thereto. Each finger has an arm 71 projecting downwardly on opposite sides of a vertical rod 72 and the arms 71 terminate in rollers 73 bearing on opposite sides of the rod, the arms being pulled toward one another by a spring 74.

The rod 72 terminates at its upper end in a cam 75, and it is apparent that when the rod is moved downward, the cam 75 enters between the rollers 73 forcing the arms 71 apart and the gripping fingers 69 and 70 upon one another. The points of the gripping fingers may be covered with suitable gripping material indicated at 71.

The rod 72 is operated, through the cam α on the main drive shaft 65, through the following mechanism, see Figures 1 and 2. The lower end of the rod is pivoted to the horizontal arm 78 of a bell crank lever 79 pivoted to the frame, as at 80, and having a vertical arm 81 projecting into a slot 82 in the sleeve 55. A spring 83 in said slot tends to move rod 72 upwardly and motion in the opposite direction is imparted through a slide pin 84 driven by one arm of a second bell crank lever 85 pivoted in the frame, as at 86, the latter bell crank lever being operated by a vertical rod 87 in the main frame, which is acted on by a third bell crank lever 88 pivoted in the main frame, as at 89, and operated by the cam α on the main shaft 65.

With the shaft 65 rotating counterclockwise, it will be noted from the position and shape of the cam, that the position of the rod 72 will remain substantially the same during the first quarter of a revolution; that the rod will be pulled downward for causing the gripping fingers to close upon one another during the second quarter of the revolution and will retain the gripping fingers in that position during the third quarter of the revolution, while the spring 83 will move the rod 72 upward for opening the gripping fingers during the last quarter of the revolution.

The operation of the gripping means is timed to correspond to the operation of the swinging frame supporting the gripping means, and the gripping fingers are made to drop the bag just before the frame reaches the end of its forward swing. Slight variations in the timing of the gripping means may be brought about by raising and lowering of the pivot 89 by means of an eccentric mounting indicated in the drawing.

After a completed bag with the trailing ribbon has been advanced by the gripping device, by the intended length of one bag, the projecting bag is separated from the ribbon by the cutting means which may be described as follows:

A stationary cutter blade 90 is mounted transversely over the front edge of the machine at an elevation slightly higher than the forming plate 14 with its rear forming the cutting edge. The movable cutter 91 is mounted for reciprocating motion in a substantially vertical plane for co-action with the rear edge of the stationary blade in cutting through the ribbon of material.

The movable blade is carried by the frame 92 supported at the forward end of a bell crank lever 93 pivoted in the main frame, as at 94. The rear end of the bell crank lever is actuated for cutting action by a spring 95, and for reverse movement, by a cam ϵ on the main shaft 65, the cam being shown in part in Figure 1 and in full in Figure 6.

The movable cutter blade 91 is pivoted in the frame 92, as at 96, a spring 97 urging the movable blade toward the stationary blade, and a set screw 98 serving to correctly position the movable blade so that it will just clear the stationary blade on the upward movement of the former.

It will be seen that in this manner the movable cutting blade can be adjusted with respect to the stationary blade with great precision. The movable cutting blade is formed with a slant from its leading edge to its trailing edge to produce a scissor-like action.

By the time the cutting action is completed, a movable template 99, the operation of which will be described later, has moved to overlie the front edge of the forming plate to bear down on the ribbon, which at this time is formed into the shape of a tube, while a small portion of the ribbon projects beyond the forming plate. This projecting portion of the ribbon is now folded over the template by the hooked finger 100, which is pivoted in the frame 92, as at 101, and which is acted on by a spring 102 to normally occupy a position where it leans against the rear face of the movable cutting blade 91.

As soon as the cutting action is completed, a cam 103 fixed relative to the finger 100, strikes one of the flanges 34 and causes the finger to turn over the front edge of the forming plate for folding the projecting end of the ribbon over the template 99.

In this manner the cutting and folding is done by a relatively simple mechanism operated by γ

single main cam. It should be noted that the cam is used for retracting the cutter, while the spring 49 is relied on to produce the cutting action so that in case of accident, as for instance, by the operator getting his finger caught between the cutting blades, the spring will yield and no serious injury will result.

The template 99 is a plate mounted transversely over the front section of the forming plate and is actuated by means of two vertical pins 105 extending loosely through the plate and forming part of a bell crank lever 106 pivotally mounted on a transverse shaft 107. The other end of the bell crank lever is actuated by the cam b on the main shaft 65 for normally holding the template in retracted position and for advancing the same toward the front edge of the forming plate for the folding operation.

After the cutting and folding operations have been completed and the template has been retracted, the heaters carried by the heater frame become active. It will be remembered that at this time, the ribbon of Cellophane is folded about the forming plate in a manner illustrated in Figure 3 with side creases formed by the plates 41 and marginal portions overlapping substantially on the longitudinal center-line of the forming plate. A projecting end of this ribbon has been turned over backwards over the template 99 and the latter has been retracted to clear the fold, which will become the bottom of the next bag. At this time, the heater frame is made to come down to apply heat and pressure to the bottom seam and to a spaced section of the longitudinal seam, the spacing being made necessary to accommodate the template in its retracted position.

The heater frame carries, at its extreme end, and overlying the bottom seam, a transverse heater 110, and spaced therefrom a second heater 111 arranged over a portion of the longitudinal seam. Since, due to this construction, there is a break between the transverse heater and the longitudinal heater, which would leave a small portion of the longitudinal seam adjacent the bottom seam unsealed, we make the longitudinal heater sufficiently long to seal at least a portion of the next bag. This offers the advantage that the advance portion of each bag reaches the front edge of the heater frame with its longitudinal seam already sealed, which not only facilitates the folding operation, but also produces a more perfect bottom seam, since without the pre-sealing of an advance portion, a small section of the longitudinal seam would remain unsealed in view of the fact that a small portion of the seam has to be made to project beyond the forming plate to furnish a gripping edge for the gripping means.

The heater frame 41, which is hinged at its rear end, as at 48, is operated by two rods 112, see Figures 4 and 5, rising from a transverse bar 113, which latter has two downwardly projecting lugs 114, slotted as at 115, to straddle the main shaft 65 on opposite sides of a cam c adapted to bear down on a roller 116 supported in the lugs underneath the cam. As the cam rotates, it forces the heater frame downward upon the forming plate and the interposed seam of the Cellophane, while the heater frame is raised by the heavy spring 49 when the cam releases its downward pressure.

A very simple way of connecting the rods 112 to the heater is illustrated in Figures 4 and 5. The heater frame has arms 117 projecting therefrom in opposite directions and these arms are

formed with notches 118 in the rear edges, the notches being positioned for engagement by the rods 112, which latter are formed with heads 119 bearing on the upper faces of the arms 117 when properly positioned. The lugs 114 have a small bracket 120 projecting rearwardly therefrom and this bracket is acted on by a spring 121 to urge the rods 112 forwardly.

This construction makes the attaching and detaching of the heater frame to and from its operating mechanism very simple. The drawings show the heater frame attached in working position. To detach the frame, it is merely necessary to pull the head 119 of the rod 112 backward, to clear the notches 118. The spring 49 will then lift the heater frame into an out-of-the-way position. To re-attach the frame, it is pressed downward, while the rods 112 are pressed rearward to bring the rods opposite the notches 118, whereupon they are made to enter the notches, which completes the attaching operation. The spring 121 continuously urges the rods 112 forward and prevents accidental disengagement. The plates 41 are provided with suitable slots 122 to accommodate the rods 112.

The operation of the machine may be briefly described as follows:

In the position shown in Figure 1, a cutting operation has been completed and the hooked finger 100 has turned a projecting end of the ribbon of material over the template 99. The next steps include the retracting of the template, the downward movement of the heaters to seal the bottom seam and the longitudinal seam and the downward movement of the cutter frame 92. Thereupon the gripping means 15 moves backward underneath the stationary cutter and into engagement with the forward end of the bottom seam, the grippers close upon the bottom seam and move backward, thereby pulling forward the entire ribbon of material by the length of one bag. The heaters, of course, are allowed to move upward before the ribbon is pulled forward.

As the advance end of the ribbon reaches the proper position, the cutter cuts off the length of one bag and the grippers open to drop the bag, while the template 99 moves forward and the finger 100 folds the projecting end of the ribbon of material over the template to prepare a new seam ready for sealing.

The individual movements of the various parts of the machine may be readily traced as follows:

The five cams a, b, c, d and e are mounted on the main shaft 65 in the order indicated by the letters, the cam a being adjacent the near side of the frame, as viewed in Figure 1, and cam e adjacent the far side. The main shaft 65 rotates counter-clockwise.

Taking the cams in their order, cam a operates the grippers 67-68, which are shown open in Figure 1. According to the shape of the cam, they will remain open during the next quarter of revolution, will then close during the second quarter, remain closed during the third quarter, and will open again during the last quarter.

Cam b operates the template 99 which is shown in Figure 1 as being in its front position or rather as having initiated its rearward movement. On further rotation of the cam, the rearward movement will be completed and the template will be held in its rearward position substantially through three-quarters of a revolution, whereupon it is allowed to move into advanced position for a brief period during the fourth quarter of the revolution.

The third cam *c* operates the heater which is shown as having initiated its downward movement. It will be further pressed downward into active position with respect to the seams to be sealed and will be held in that position during the first quarter and a substantial portion of the second quarter of a revolution, whereupon it is allowed to be lifted by the spring *49* and stays in raised position during the third and most of the fourth quarter of the revolution.

The fourth cam *d* (see Figure 7), operates the swinging frame *16*, which is shown in Figure 1 as being in its most advanced position. As the cam *d* rotates, it pulls the swinging frame *16* toward the work during the first quarter of the revolution, continues to pull at a decreased rate of speed during the second quarter, slowly reverses the movement during the third quarter, and swings forward to its original position during the last quarter of the revolution. It will be noted that when the gripping means reaches the seam, it comes to a momentary stand-still while its movement is reversed. This momentary stand-still coincides with the time when cam *a* causes the gripping fingers to close.

Cam *e* operates the movable cutter and the folding finger *100*. The cutter is shown as having completed its cutting action and the folding finger as having performed the folding operation, and Figure 6 shows cam *e* positioned to correspond to the position of the cutting blade. On the next quarter of a revolution, the cutting blade will be retracted, will be held in retracted position during the second and third quarter of the revolution, and will be allowed to move back to cutting position under the influence of spring *95* during the fourth part of the revolution.

The folding finger *100* moves as part of the cutter supporting frame and receives its final impetus to fold over the projecting end of the ribbon by the cam *103* striking the flange *34* of the main frame. This is timed to take place immediately after the cutting action is completed.

While our machine has been described as particularly adapted for use on material such as Cellophane which may be sealed by mere application of heat under pressure, it is apparent that most of the features as readily apply to a material which requires glue or other adhesive for sealing. In that case any conventional means could be provided for feeding the glue and the heating means might be omitted from the heater frame, the latter being used as a pressure means only, or as a means for conveying a small amount of heat.

We claim:

1. In a bag forming machine, means for mounting a ribbon of material with freedom of lengthwise movement, means for forming the advance end of the ribbon into a bag, a carrier frame rockably mounted with respect to the advance edge of the bag, gripping means carried by the frame, means for operating the frame to alternately move the gripping means toward the advance edge of the bag and in reverse direction and means for adjusting the angle of rocking movement of the carrier frame arranged to bring the carrier to the same point on its forward swing regardless of the length of its rearward swing.

2. In a bag forming machine, means for mounting a ribbon of material with freedom of lengthwise movement, means for forming the advance end of the ribbon into a bag, a carrier frame rockably mounted with respect to the advance edge of the bag, gripping means carried by the

frame, means for operating the frame to alternately move the gripping means toward the advance edge of the bag and in reverse direction, the said operating means including a rocking shaft having an arm projecting therefrom with a curved slot in the arm and a connecting link pivoted to the carrier frame and to the arm by means of the slot, the curve of the slot being such as to bring the carrier frame to the same point on its forward swing regardless of the adjustment with respect to the rearward swing.

3. In a bag forming machine, means for revolvably mounting a roll of material for feeding a ribbon of material therefrom, means engaging the front end of the ribbon for intermittently advancing the ribbon a specified distance, means for forming an intermediate portion of the ribbon into a tube during the advance, means for cutting the ribbon at the end of each advance and at a point spaced from the front edge so as to present a new front edge means for turning the new front edge over the tube to form a closure therefor and a common drive means for the advancing means, the cutting means and the turning means for operating the same in timed relation.

4. In a bag forming machine, means for revolvably mounting a roll of material for feeding a ribbon of material therefrom, means engaging the front end of the ribbon for intermittently advancing the ribbon a specified distance, means for forming an intermediate portion of the ribbon into a tube during the advance, means for cutting the ribbon at the end of each advance and at a point spaced from the front edge so as to present a new front edge, a bar extending transversely across the width of the ribbon so as to rest thereon, means for intermittently moving the same lengthwise of the ribbon between an advance position near the front edge of the tube and a retracted position parallel therewith, and means for turning the new front edge over the advancing bar to form a closure for the tube.

5. In a bag forming machine, means for revolvably mounting a roll of material for feeding a ribbon of material therefrom, means engaging the front end of the ribbon for intermittently advancing the same a specified distance, means for forming an intermediate portion of the ribbon into a tube during the advance, with overlapping longitudinal edges, means for cutting the ribbon at the end of each advance and at a point spaced from the front edge so as to present a new front edge, a bar extending transversely across the width of the ribbon so as to rest thereon, means for intermittently moving the same lengthwise of the ribbon between an advance position near the front edge of the tube and a retracted position parallel therewith, means for turning the new front edge over the advanced bar to form a transverse closure for the tube, two heating elements, one being transverse and one longitudinal, and means for pressing the same upon the turned front edge and the longitudinal overlap for sealing the same when the bar is retracted, the heating elements being spaced by a distance equal at least to the width of the bar so as to accommodate the latter therebetween.

6. In a bag forming machine, means for revolvably mounting a roll of material for feeding a ribbon of material therefrom, means engaging the front end of the ribbon for intermittently advancing the same a specified distance, means for forming an intermediate portion of the ribbon into a tube during the advance, with over-

lapping longitudinal edges, means for cutting the ribbon at the end of each advance and at a point spaced from the front edge so as to present a new front edge, a bar extending transversely across the width of the ribbon so as to rest thereon, means for intermittently moving the same lengthwise of the ribbon between an advance position near the front edge of the tube and a retracted position parallel therewith, means for turning the new front edge over the advanced bar to form a transverse closure for the tube, two heating elements, one being transverse and one longitudinal, and means for pressing the same upon the turned front edge and the longitudinal overlap for sealing the same when the bar is retracted, the heating elements being spaced by a distance equal at least to the width of the bar so as to accommodate the latter therebetween, and the length of the longitudinal element being sufficient to seal in each operation that portion of the overlap covered by the transverse member in the next operation.

7. In a bag making machine, means for intermittently advancing a ribbon of material for bag-forming operations, a heating device mounted over the ribbon with freedom of swinging movement in the vertical plane of the ribbon, means urging the heating device away from the ribbon, a transverse shaft underneath the ribbon having a cam thereon, a forked member straddling the cam, and having slots in which the shaft is slidably received, a roller at the end of the forked member for the cam to operate against, a transverse member carried by the forked member and having prongs projecting upwardly therefrom, arms projecting from the heating device having notches therein for receiving the prongs, and spring means urging the prongs into the notches, the prongs having heads bearing down on the margins of the notches.

8. In a bag forming machine, means for intermittently advancing a ribbon of material for bag forming operations including means for folding the same to form a tube, a stationary cutter mounted over the tube, a movable cutter mounted underneath the tube for coaction with the former cutter in cutting the tube, means for moving the movable cutter, a bar, means for moving the same to overlie the tube near the cutters, a folder carried by the movable cutter so as to move therewith and means on the folder cooperable with a fixed member for swinging the folder around the bar for folding the cut end of the tube over the bar.

9. In a bag making machine, a mandrel having a front edge substantially fitting within a bag to be made, means for advancing material over the mandrel from the rear in intermittent movement to form a sleeve embracing the mandrel and extending forwardly therefrom substantially by the length of a bag at the end of each movement, means for cutting the sleeve at a point spaced slightly from the front edge of the mandrel so as to leave a small projecting portion of the sleeve in front of the mandrel free for folding operations, and means for operating the cutting means in timed relation to the advancing means.

10. In a bag making machine, a mandrel having a front edge substantially fitting within a bag to be made, means for advancing material over the mandrel from the rear in intermittent movement to form a sleeve embracing the mandrel and extending forwardly therefrom substantially by the length of a bag at the end of each

movement, means for cutting the sleeve at a point spaced slightly from the front edge of the mandrel so as to leave a small projecting portion of the sleeve in front of the mandrel free for folding operations, a bar extending transversely across the width of the sleeve so as to rest thereon, means for moving the bar lengthwise of the sleeve toward the front edge of the mandrel, means for folding the projecting portion over the bar, and means for retracting the bar to a parallel position.

11. In a bag making machine, a mandrel, means for mounting the same horizontally with freedom of slight vibratory movement of the front section of the mandrel, a supporting element for the front section of the mandrel, means for advancing material over the mandrel in intermittent movement with a thickness of material between the mandrel and the supporting element and overlapping side margins on top of the mandrel, a heater, means for pressing the same upon the overlapping side margins for sealing the same, whereby the mandrel is pressed upon its supporting element, the advancing means being constructed to exert a slight upward pull on the sleeve for relieving the pressure on the thickness of material confined between the mandrel and the supporting element.

12. In a bag making machine, a mandrel, means for mounting the same horizontally with freedom of slight vibratory movement of the front section of the mandrel, a supporting element for the front section of the mandrel, means for advancing material over the mandrel in intermittent movement with a thickness of material between the mandrel and the supporting element and overlapping side margins on top of the mandrel, a heater, means for pressing the same upon the overlapping side margins for sealing the same, whereby the mandrel is pressed upon its supporting element, and means for exerting a slight lifting effect on the mandrel as the material advances for relieving the pressure on the thickness of material confined between the mandrel and the supporting means.

13. In a bag making machine, a forming plate adapted to have a bag formed thereon with a transverse bottom seam and a longitudinal seam, a bar extending transversely across the plate to aid in forming the bottom seam and being retractable to an inactive position, and a heating means for the seams comprising a supporting bracket, a heater arranged transversely thereon for sealing the bottom seam and a second heater mounted longitudinally thereon for sealing the longitudinal seam, the second heater being spaced from the first heater to allow clearance for the retracted bar.

14. In a bag making machine, a frame, means for revolvably mounting a roll of material thereon for feeding a ribbon from said roll, a mandrel arranged longitudinally with respect to the ribbon and having lateral grooves therein, means for passing an intermediate portion of the ribbon over the mandrel to form a tube, creasing plates adapted to project into the grooves from opposite sides, a pair of shafts extending transversely across the frame, a pair of brackets on each shaft for supporting the creasing plates, reverse threads on each shaft for driving the brackets toward or away from each other, and a driving connection between the two shafts.

15. In a bag making machine, a mandrel adapted to have a bag formed thereon, means for horizontally mounting the mandrel, a shaft mounted

below the mandrel, a frame having a pivoted support at its lower end below the front end of the mandrel and having an upper end rockable toward and away from the front end of the mandrel, gripping members carried by the upper end of the frame, means for operating the gripping members including a cam rod and a member slideable in co-axial relation to the frame, means operated by the shaft for rocking the frame, and means operated by the same shaft for driving the slideable member whereby the gripping members are made to act in timed relation to the rocker frame movements.

16. In a bag machine, a mandrel adapted to have a bag formed thereon, a frame, means for rockably supporting the same with freedom of movement of one end thereof toward and away from the mandrel, gripping members carried by said end, means for operating the gripping members including a member slideable in co-axial relation to the frame, a revolvable shaft, a driving connection between the shaft and the frame, and a driving connection between the shaft and the slideable member, whereby the gripping members are made to act in timed relation to the frame movements.

17. In a bag making machine, a mandrel adapted to form bags thereon from a continuous ribbon, means engaging the front end of the ribbon for intermittently advancing the same a specified distance, the said means including a pair of gripping members, a movable carrier for the same and means for operating the carrier and the gripping means in timed relation whereby the gripping means release the front end of the ribbon before the carrier reaches the end of its movement.

18. In a bag making machine, a mandrel adapted to have a ribbon of sheet material arranged thereon in tubular form, means for intermittently advancing the material, means for cutting the material a short distance ahead of the mandrel to leave a projecting portion, means for folding the projecting portion over the mandrel, and means for operating the cutting means and the folding means in automatic succession.

19. In a bag forming machine, a mandrel adapted to have a ribbon of sheet material arranged thereon in tubular form, means for intermittently advancing the material, a cutter blade mounted above the ribbon slightly forward of the mandrel, a lever mounted underneath the mandrel and having a second cutter blade for cooperation with the first blade in cutting the ribbon so as to leave a portion projecting beyond the mandrel, and a folder carried by the lever for cooperation with a fixed element in folding the projecting portion over the mandrel.

20. In a bag making machine, a mandrel adapted to have a ribbon of sheet material arranged thereon in tubular form, means for intermittently advancing the ribbon, a bar extending transversely across the mandrel so as to rest on the ribbon and being made to project beyond the sides of the mandrel, and means engaging the projecting ends of the bar for sliding the bar back and forth over the material in timed relation to the intermittent advance movements.

21. In a bag forming machine, a mandrel, means for folding sheet-like material about the mandrel in tubular form, means for mounting the mandrel horizontally with a slight vibratory movement of the front section of the same, a supporting element for the front section of the mandrel, a heater, means for intermittently pressing the same upon the material for sealing the same whereby the mandrel is pressed upon the supporting element, and means for advancing the sheet material after each heating operation with a slight lifting effect for relieving the pressure on the material confined between the mandrel and the supporting element.

22. In a bag making machine, a mandrel adapted to have sheet-like material folded thereabout in tubular form with overlapping edges on top of the mandrel, means operable for intermittently advancing the material a specified distance, means adapted for cutting the material a slight distance forward of the mandrel after each advance and for folding the projecting portion of the material over the front edge of the mandrel to form an overlap, means adapted for heat-sealing the overlapping portions of the sheet material, and means for operating the advancing means, cutting and folding means, and the heat-sealing means in timed relation.

23. In a bag making machine, a mandrel adapted to have sheet-like material folded thereabout in tubular form with overlapping edges on top of the mandrel, means operable for intermittently advancing the material a specified distance, means adapted for cutting the material a slight distance forward of the mandrel after each advance and for folding the projecting portions of the material over the front edge of the mandrel to form an overlap, means adapted for heat-sealing the overlapping portions of the sheet material, a revolvable shaft underneath the mandrel, and means for operating the advancing means, the cutting and folding means and the heat-sealing means from the shaft in timed relation.
